GARMENT

Sidney Wellins, Cedarhurst, and Murray Wellins,
Lawrence, N. Y.

Application March 31, 1939, Serial No. 265,090

4 Claims. (CL. 2-76)

This invention relates to garments. It is particularly directed to a maternity skirt or dress adjustable to accommodate varying sizes of the waist of the wearer.

An object of this invention is to provide a garment of the character described, which shall be relatively inexpensive to manufacture, easy to adjust, comfortable to wear, attractive in appearance, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a front perspective view of a garment embodying the invention, illustrated in the form of a skirt;

Fig. 2 is a front elevational view of the upper portion of the skirt opened up to full size;

Fig. 3 is a partial perspective view of a portion of the skirt;

Fig. 4 is a cross-sectional view taken on line 4-4 of Fig. 2;

Fig. 5 is a cross-sectional view taken on line 5-5 of Fig. 2;

Fig. 6 is a front perspective view of a dress embodying the invention;

Fig. 7 is an enlarged, front, elevational view of a portion of the dress shown in Fig. 6, opened up to full width;

Fig. 8 is a cross-sectional view taken on line 8-8 of Fig. 7;

Fig. 9 is a front perspective view of a garment embodying the invention, and illustrating a modified construction; and

Fig. 10 is a front perspective view of the garment shown in Fig. 9, with the smock removed.

Referring now in detail to the drawings, 10 designates a garment embodying the invention, shown for the purpose of illustration in the form of a skirt. The skirt 10 has at the front thereof, and adjacent the upper end thereof, an insert 12 stitched to the skirt on a line of stitching 13.

The insert 12 is made of a piece of cloth preferably similar to the cloth of which the rest of the skirt is made, but cut on a bias, as shown in Fig. 2 of the drawings, with the woof and warp

threads running in inclined direction to the vertical.

The piece of cloth 12 is fan shaped having upwardly and outwardly inclined side edges 14, and a curved bottom edge 15, interconnecting the inclined side edges 14. The upper or top edge 17 of the piece of cloth 12 is rounded, being higher at the middle than at the ends, as shown in Fig. 2 of the drawings.

10 The cut edge 19 of the skirt 10 which accommodates the insert 12 is U-shaped, as shown in Fig. 1 of the drawings, the insert 12 comprising more cloth than the portion of the skirt 10 which is cut away to accommodate the insert, whereby the 15 insert 12 provides a fullness allowing for expansion of the waist of the wearer during pregnancy, as will be more fully explained hereinafter.

The length of the upper edge 17 of the insert 12, is greater than the normal length between 20 the points 22 of the skirt, at the upper ends of the cut edge 19, whereby to increase the normal waistline of the skirt.

The insert 12 may be formed with a plurality of pleats 24 diverging upwardly, whereby to take 25 up the fullness of the insert when the pleats are in folded condition.

Means is provided for taking in or shortening the upper edge of the insert 12, whereby to reduce 30 the waistline of the garment. To this end, there is stitched to the inner side of the insert 12 along its upper edge 17, a strip 28 stitched along three parallel lines of stitching 29, 30 and 31, forming two parallel, co-extensive tubular pockets 33 and 34. Each tubular pocket is open at one end. The 35 upper tubular pocket 33 is closed at one end 31, and the lower pocket 34 is closed at the other end 38.

Extending within the upper tubular pocket 33 40 is an elongated flexible strap 39, stitched to the closed end 31 of the pocket. Strap 39 extends beyond the other open end of said pocket. Disposed within the lower tubular pocket 34 is an elongated flexible strap 40, stitched at the closed end 45 38 of said pocket, and projecting beyond the open end of the pocket.

Stitched to the skirt 10, adjacent the open end of the tubular pocket 34, is one end of a strap 42, and stitched to said skirt adjacent the open 50 end of the tubular pocket 33, is one end of a strap 44.

To reduce the waistline of the skirt, the ends of the straps 39 and 40 are pulled in opposite directions causing the upper edge of the insert 12 to be shortened and exposing greater lengths of

said straps. The straps are pulled in until the skirt fits snugly around the waistline of the wearer. The strap 39 may then be tied into a bow 45 with the strap 44; and the strap 40 may be tied into a bow 46, with the strap 42. When the straps 39 and 40 are pulled, the pleats 24 take up the fullness of the insert 12.

It will be noted that the straps 39 and 40 are conveniently located where they may be easily grasped by the two hands of the wearer, and pulled in opposite directions to draw the waistline of the skirt snugly against the wearer's body. The straps 39 and 44 may then be conveniently tied into bows with the straps 40 and 42.

In Figs. 6, 7 and 8 there is shown a garment 10a, embodying the invention, and illustrating a modified construction. The garment 10a, for the purpose of illustration, is in the form of a dress, and is cut full at the waistline to permit expansion at that part of the garment.

Stitched to the inside of the dress, at the front of the dress, and at about the waistline of the latter, is a horizontal strip 50 of cloth stitched on three parallel, co-extensive lines of stitching 51, 52 and 53, forming a pair of parallel similar, upper and lower co-extensive tubular pockets 54 and 55.

One end 54a of the tubular pocket 54 is closed. The dress is formed with an opening 56 communicating with the other end of the pocket 54. The lower pocket 55 has an opposite closed end 57, and the dress has an opening 58 communicating with the end of said tubular pocket opposite its closed end.

Within the upper pocket 54 is a flexible strap 60, stitched to the closed end 54a of said pocket, and passing through the opening 56 to the outside. In the lower pocket is a strap 61 stitched to the closed end 57, and passing through the opening 58 to the outside. The waist portion of the dress may be gathered in or decreased in girth by pulling in opposite directions on the ends of the straps 60 and 61.

Means is provided to tie the straps 60 and 61 to retain the dress in adjusted position. To this end, there is stitched to the dress, at the waistline thereof, as at 65, an elongated strap 66 long enough to extend all around the back of the dress.

Strap 66 has end portions 67 and 68 extending forwardly at the front of the dress. The strap 68 may be tied in a bow 70 to the end portion of strap 60, whereas the strap end 67 may be tied into a bow 71 with the end portion of the strap 61.

In Figs. 9 and 10 there is shown a garment embodying the invention, and illustrating a modified construction. The garment 80 of Fig. 9 comprises a dress 81 and smock 82. The dress 81 has a skirt portion 83, similar to the skirt 10 of Fig. 1, and likewise provided with an insert 12 adapted to be drawn in by strings 39, 40, within pockets 33 and 34, and tied into bows 45 and 46.

Stitched to the skirt 83, however, is a waist portion 85 formed with a central, inverted, U-shaped cut-out 86, extending above the cut-out 19 in the skirt 83. The cut-out 86 permits freedom of expansion and growth of the part of the abdomen above the waistline. The smock 82 which may be of conventional construction, covers the cut-out 86 as well as the insert 12.

It will thus be seen that there is provided a device in which the several objects of this inven-

tion are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described our invention, we claim as new and desire to secure by Letters Patent:

1. A garment having at the waistline a pair of tubular, parallel, co-extensive pockets, a flexible strap within one pocket attached to one end 15 of the tubular pocket and projecting from the other end thereof, a strap within the other tubular pocket attached to an end of the second tubular pocket, adjacent the latter end of the first pocket, and projecting from an end of the 20 second pocket adjacent the first end of the first pocket, the projecting strap ends being adapted to be pulled in opposite directions for drawing in the waistline of the garment, and means on the garment for attaching the strap ends to retain the waistline of the garment against expansion.

2. A garment comprising a skirt having a U-shaped cut-out extending to the waistline thereof, an insert of cloth stitched to the U-shaped edge of the cut-out, the upper edge of 30 the insert being greater in length than the distance between the upper ends of the U-shaped cut-out, a pair of tubular pockets adjacent the upper ends of the insert, straps within said pockets, one attached at one end and the other attached at an opposite end, the free end of each strap projecting from each pocket, whereby said straps may be pulled in opposite directions to draw in the upper edge of said insert, to decrease the waistline of said skirt, and strap 40 means on said skirt adapted to be tied to the outer ends of the first straps to retain the skirt against expansion in waistline.

3. A garment comprising a skirt portion and a waist portion, said skirt being formed with a 45 cut-out at the front thereof, and extending from the waistline to below the waistline, an insert stitched to the edge of said cut-out, said insert being of greater dimension than the cut-out, to provide fullness to permit expansion of the waistline of the skirt, means for reducing the waistline of the skirt and for retaining said waistline in reduced condition, the waist portion of said 50 garment having a cut-out extending above the insert, from the waistline up at the front of said waist portion.

4. A garment comprising a skirt portion and a waist portion, said skirt being formed with a cut-out at the front thereof, and extending from the waistline to below the waistline, an insert 60 stitched to the edge of said cut-out, said insert being of greater dimension than the cut-out, to provide fullness to permit expansion of the waistline of the skirt, means for reducing the waistline of the skirt and for retaining said waistline in reduced condition, the waist portion of said garment having a cut-out extending above the insert, from the waistline up at the front of said waist portion, and a smock covering said waist portion of the cut-out therein, and the insert in the skirt portion, said insert being cut on the bias.
